REVERSING GEAR FOR STEAM ENGINES
WITH POPPET VALVE GEAR, ESPECIALLY
FOR LOCOMOTIVE AND MARINE STEAM
ENGINES

Hugo Lentz, Berlin-Halensee, Germany

Application December 16, 1935, Serial No. 54,718
In Germany December 19, 1934

4 Claims. (Cl. 121—127)

This invention relates to the construction of the reversing gear of valve steam engines, especially locomotives and marine engines with poppet valve gear, in which the valves are actuated by oscillating control cams. According to the invention the admission- and exhaust valves are separately controlled from two different oscillating points or movable parts of a reversing element (link or eccentric), so that, when adjusting 5 the gear for different charges, the path of the control points for the admission valve is always farther from the centre of the shaft than the path of the control point for the exhaust valve. Thus, with the same displacement path the angular displacement of the control point for the exhaust valve is always greater than the angular displacement of the control point for the admission valve. Different angles of lead correspond 10 to these angular displacements, the angle of lead for the admission valve being greater than that for the exhaust valve.

This presents the advantage that, with increased charge, that is when larger quantities of steam are supplied, the exhaust valves will be held open for a longer period so that in the case 15 of a large charge the compression will commence later and the larger quantity of steam can more easily flow out of the cylinder during the exhaust period. The idea of the invention is therefore, to adjust the angle of lead for the exhaust to a greater extent than the angle of lead for the admission in dependency upon the same, in order 20 to attain the above mentioned object.

Several embodiments of the invention are illustrated by way of example in the accompanying drawings, in which

Fig. 1 shows diagrammatically the end elevation of a locomotive with valve motion drive according to the invention.

Fig. 2 is a section on line II—II of Fig. 1 in larger scale.

Fig. 3 is a section on line III—III of Fig. 2 in larger scale.

Fig. 4 is a section on line IV—IV of Fig. 2.

Fig. 5 is a section on line V—V of Fig. 1 through the reversing shaft housing on larger scale, the driving gear of the reversing shafts mounted the one in the other being situated on the one side of the machine.

Fig. 6 shows a section through the valve housing situated on the one cylinder side of a steam engine controlled according to the invention, in which the admission and exhaust-valves on each cylinder side are lying side by side, and the valves 55 of each kind are controlled by a separate revers-

ing shaft, the driving gears for the reversing shafts being mounted on different sides of the engine.

Fig. 7 shows a section through the valve housing and the gear drive in a steam engine with admission- and exhaust-valve arranged the one behind the other at each end of the cylinder.

Fig. 8 is a section on line VIII—VIII of Fig. 7.

Fig. 9 shows a diagram of the eccentric adjusting.

On either side of the frame 1 the steam cylinders 2 of the locomotive are mounted. Every cylinder carries at the top the valve housing 3 in which the admission and exhaust channel for the steam, the admission and exhaust valves and in a 15 separate chamber 4 the reversing shafts with the reversing cams 12 are accommodated. In the form of construction shown in Fig. 5, the hollow reversing shaft 10 with control cams 12 acts, by means of intermediate levers 12a, upon the spindles 25 of the admission valves. Shaft 11 is mounted in the hollow shaft 10 and carries a control cam 14 which, by means of intermediate levers 14a, acts upon the spindles 26 of the exhaust valves.

The reversing shafts 10 and 11 are driven from a rotating shaft 17 transversely mounted on the frame and by means of adjusting eccentrics 22 and 23. The rods 22a and 23a of the eccentrics engage on the lever arms 10a and 11a keyed 30 on the ends of shafts 10 and 11. The hollow shaft 17 is driven from one of the driving wheels of the locomotive through a transmission gear, as disclosed in the U. S. A. application Ser. No. 114,190 filed December 4, 1936.

The adjusting eccentrics 22 and 23 are, in the form of construction shown in Figs. 2 and 3, constructed as step eccentrics, in which as shown in Fig. 3 both eccentric faces are arranged so that they correspond to the control diagram shown in 40 Fig. 9 which will hereinafter be described and that consequently the exhaust eccentric in the median position has a smaller eccentricity than the admission eccentric.

The setting body 18 is shiftably mounted in 45 a cross-section of the hollow shaft 17 limited by two ring-flanges 30 on a prismatic element 31 connecting the ring-flanges. With this object in view the setting body 18 has a longitudinal slot 32. On one side of the slot 32 a serrated plate 50 19 is inserted, the teeth of which mesh with the teeth 20 of an axially shiftable adjusting rod 21 mounted in the hollow shaft 17. The teeth are directed obliquely to the direction of adjusting so that, when the rod 21 is shifted in the direc- 55

tion of the arrow A, the setting body 18 is shifted on the prismatic element 31 in the direction of the arrow B, and inversely.

The axial shifting of rod 21 is effected thereby 5 that at the end of the same a bush 32 having obliquely adjusted teeth 34 is arranged, in which teeth the teeth 35 of a second upwardly extending adjusting rod 36 engage in such a manner that during the axial adjusting of the rod 36 10 the adjusting rod 21 is shifted in the hollow eccentric shaft 17. The end of the adjusting rod 21 with the bush 33 and the adjusting rod 36 are mounted in bores of a housing 37, said bores being directed perpendicularly the one to the 15 other. The end of the adjusting rod 36 projecting in upward direction from the housing 37 is connected with a bell crank lever 38 which, by a rod system not shown in detail, can be attended from the engineer's cab on the loco- 20 motive.

In Fig. 9 the diagram of the adjusting of the eccentricities is illustrated, OA showing the smallest eccentricity of the discharge eccentric and OE the smallest eccentricity of the admission eccentric for zero-charge. If both eccentricities are shifted by the adjusting rod 21 by the same distance, E is displaced, for instance if the charge amounts to 20%, to E' and point A to A'. OE' 25 is then the effective eccentricity for the admission and OA' the effective eccentricity for the exhaust, the angular displacement for the exhaust being greater than the angular displacement for the admission. The exhaust valve is therefore maintained open, with larger charge, 30 for a longer time so that the compression begins later.

In Figs. 2 and 3 the two eccentrics 22 and 23 are united on one adjusting body. The two eccentrics may, however, be arranged separate the 40 one from the other on the hollow shaft 17 and actuated from the same adjusting rod 21 but with different tooth pitches. This arrangement is for instance employed in the valve arrangement shown in Fig. 6, in which in the gear housing 16 the lay shaft 10 with the admission control cam 12 is situated on the one side of the cylinder and the control shaft 11 with the control cam 14 for controlling the exhaust valve is situated on the other side of the cylinder.

50 In Figs. 7 and 8 a valve arrangement with its

control gear is shown, in which the admission and exhaust valves are situated co-axially one behind the other at each end of the cylinder and the spindle 25 of the admission valve 13 extends through the hollow spindle 26 of the exhaust valve. Discs mounted on the ends of the two valve spindles bear against the ends of intermediate levers 33 actuated by the operating cranks 12, 14 of the lay shafts 10 and 11. The cranks and the intermediate levers contact after 10 the manner of rolling levers. As can be seen, it is also possible in this arrangement to separately adjust the admission and exhaust valves in the sense of the invention.

I claim:—

1. A reversing gear for steam engines, especially for locomotive and marine steam engines with poppet valve gear with oscillating control cams, comprising in combination with the admission and exhaust valves, a shaft, a reversing 20 element on said shaft having two differently oscillating control points adapted to actuate said admission and exhaust valves respectively, means for adjusting said element for different charges, the path of the control point for the admission 25 valve being away farther from the centre of the shaft than the path of the control point for the exhaust valve, so that during the adjustment the angles of advance for the admission valve and the exhaust valve change so that the exhaust 30 valve is held open longer as the charge increases.

2. In a reversing gear as specified in claim 1, a double-adjusting eccentric, and two differently adjusted driving eccentrics for the admission valves and for the exhaust valves.

3. In a reversing gear as specified in claim 1, a double-adjusting eccentric, and two differently adjusted driving eccentrics for the admission valves and for the exhaust valves, the eccentric for operating the exhaust valves having 40 a smaller eccentricity than the eccentric for operating the admission valves.

4. In a reversing gear as specified in claim 1 eccentrics for the admission valves and eccentrics for the exhaust valve arranged separately the one 45 from the other, and an adjusting rod for operating all said mechanisms and having teeth with different pitches one pitch for each eccentric.

HUGO LENTZ. 50
